FREDERIC S. PINKHAM, OF BOSTON, ASSIGNOR TO HIMSELF AND EDWARD FOSTER,
OF MIDDLEBOROUGH, MASSACHUSETTS.

Letters Patent No. 85,956, dated January 19, 1869.

IMPROVEMENT IN HOLDERS FOR BROOM AND BRUSH-HANDLES.

The Schedule referred to in these Letters Patent and making part of the same.

To all persons to whom these presents shall come:

Be it known that I, FREDERIC S. PINKHAM, of Boston, in the county of Suffolk, and State of Massachusetts, have invented a new and useful Improvement in Brooms or Brushes; and do hereby declare the same to be fully described in the following specification, and represented in the accompanying drawings, of which—

Figure 1 is a side elevation,

Figure 2, an edge view, and

Figure 3, a longitudinal section of a house-broom provided with my invention.

In carrying out my invention, I combine with or apply to the handle or pole of a broom, an auxiliary suspension-handle, which I prefer to so apply to the broom-handle as to be adjustable or movable lengthwise thereof, and be capable of being fastened in position thereon by a clamp-screw, or its equivalent.

During the process of sweeping with a broom by a person, when grasping its handle by both of his or her hands, the lower hand is employed to press the broom along, the upper hand being used for steadyng it. The lower hand consequently is liable to be chafed or calloused between the thumb and fore-finger; and besides, by such hand being out of its normal position while grasping the handle, the wrist is apt to soon become more or less fatigued.

With my improvement, the lower hand, while the broom is in operation, is in its natural position, and grasps the auxiliary handle, the part of which that is held in the hand being disposed at right angles with the main handle, in manner as represented in the drawings.

In such drawings, A denotes a common broom, of which a is the handle.

The auxiliary or suspension-handle is shown at B as projecting from a tube or collar, b, which loosely encompasses the handle a, and is provided with a clamp-screw, c, or other suitable means of fixing it in any desirable position.

This clamp-screw is screwed into the pipe and against the handle a, and serves to fix the tube or collar in any desirable position on such handle.

The auxiliary or bow-handle, formed as represented, consists of a metallic wire, h, bent in the form of a yoke or bow, it being fastened at or near its ends to the slider or collar. It may have a wooden cylinder, d, applied to it, and such cylinder may turn freely on the straight middle part of the bow.

This cylinder is to be grasped by one hand of a person while using the broom, the other hand being applied to the main handle at or near its upper end.

This addition to a broom enables a person to sweep with it much more easily and to better advantage than he can without it.

I claim the combination and arrangement of the broom and the auxiliary suspension-handle B, provided with means for adjusting and fixing it in position on the handle of the broom, as set forth.

I also claim the said handle as composed of the sliding collar, the clamp-screw, and the wire or bow, h, or such, and the cylinder d, the whole being for application to and use with a broom, in manner as specified.

FRED. S. PINKHAM.
